UNITED STATES PATENT OFFICE.

GEORGE SCHRODER, OF BERKELEY, CALIFORNIA.

FOUNTAIN INK-BOTTLE.

1,266,326.

Specification of Letters Patent. Patented May 14, 1918.

Application filed January 9, 1918. Serial No. 211,027.

To all whom it may concern:

Be it known that I, GEORGE SCHRODER, a citizen of the United States, residing at Berkeley, in the county of Alameda and State of California, have invented certain new and useful Improvements in Fountain Ink-Bottles; and I do hereby declare the following to be a full, clear, and exact description of the invention, such as will enable others skilled in the art to which it appertains to make and use the same.

This invention relates to improvements in ink bottles for commercial use, and has for one of its objects the provision of a device of this character, whereby it may be positioned or laid upon its side to produce an efficient fountain ink well that will at all times feed ink to the fountain to keep the same full.

Another object of this invention is the provision of one of the walls of the bottle inclined in the direction of the neck or fountain, so that the entire amount of ink in the body will drain into the fountain as it is used.

A further object of this invention is the provision of a cap adapted to be secured to the neck or fountain, so as to close the same when desired, thereby producing a device which can be carried while traveling without the danger of the ink spilling.

A still further object of this invention is the provision of a fountain ink bottle of the above stated character, which shall be simple, durable and efficient, and which may be manufactured and sold at a comparatively low cost.

With these and other objects in view, which will become more apparent as the description proceeds, the invention consists in certain novel features of construction, combination, and arrangement of parts, as will be hereinafter more fully described and claimed.

For a complete understanding of my invention, reference will be had to the following description and accompanying drawing, in which:

Figure 1 is a front elevation of a fountain ink bottle constructed in accordance with my invention,

Fig. 2 is a longitudinal sectional view of the same, illustrated positioned upon its side, so that the ink will pass into the neck or fountain, and

Fig. 3 is a sectional view, taken on the line 3—3 of Fig. 2.

Referring in detail to the drawing, the numeral 1 indicates the body of the bottle which is of substantially rectangular shape in formation and preferably constructed from glass, but may be constructed from any other material suitable for the purpose. The body 1 consists of a bottom wall 2, having side walls 3, and a top inclined wall 4 that terminates into a neck 5. The neck 5 is also formed upon one of the side walls 3, which is of an increased thickness over the other side wall and inclined as shown at 3', so that the contents of the body will flow into the neck when positioned upon its side, as illustrated in Fig. 2, the side wall of increased thickness acting as a support to the body. A portion of the neck 5, which is formed integrally with the inclined top wall 4 of the body, is of increased thickness, as illustrated at 6, and provided with an opening 7 extending therethrough and in communication with the bore of the neck, which opening is adapted to permit the pen or like instrument to be inserted into the neck, which forms a fountain to the body, so that the pen or instrument may receive ink. The outer end of the neck 5 is closed by a cork or stopper 8 of any desired construction after the body has been filled when in an upright position.

The neck or fountain 5 is provided with screw threads 9, adjacent its formation to the body, and threaded thereon is a cap 10 that is adapted to fit over the neck or fountain to close the opening 7, and has its open end threaded for coöperation with the threads 9 upon the neck or fountain.

From the foregoing description, taken in connection with the accompanying drawing, it will be noted that an ink bottle has been provided which can be readily used for commercial use, that is one whereby the ink may be sold in the bottle and then be used as a fountain ink well by the purchaser. It will also be noted that this ink bottle can be readily carried from one point to another without danger of the ink spilling therefrom.

While I have shown and described the preferred embodiment of my invention, it will be understood that minor changes in construction, combination and arrangement of parts may be made without departing

from the spirit and scope of the invention as claimed.

Having thus described my invention what I claim as new is:

- 5 1. A fountain ink bottle comprising a substantially rectangular body having one side wall of increased thickness and inclined to form a support for the body when positioned upon its side, said body having an inclined top wall, a neck formed upon the top wall and side walls of the body and having openings in the side and end thereof, a cork for closing the end opening of the neck, and means adapted to be threaded upon the neck 10 for closing the side opening therein.
15 2. An ink bottle comprising a substantially rectangular body having one side wall

of increased thickness and inclined upon its inner face and adapted to support the body when upon its side, said body having an inclined top wall, a neck formed on said body and having a thickened portion provided with an opening to receive a pen and an opening in the end thereof, a cork closing the end opening of said neck, screw threads 20 on said neck, and a screw threaded cap threaded to the neck for closing the first-named opening.

In testimony whereof I affix my signature in presence of two witnesses.

GEORGE SCHRODER.
